POULTRY COOP

Filed Jan. 12, 1925

UNITED STATES PATENT OFFICE.

SETH S. BARKER, OF OTTUMWA, IOWA.

POULTRY COOP.

Application filed January 12, 1925. Serial No. 1,887.

To all whom it may concern:

Be it known that I, SETH S. BARKER, a citizen of the United States, residing at Ottumwa, in the county of Wapello and State 5 of Iowa, have invented a certain new and useful Poultry Coop, of which the following is a specification.

The object of my invention is to provide a poultry coop of simple, durable and comparatively inexpensive construction.

More particularly, my invention relates to a poultry coop adapted to be made in sections, which can be readily and easily assembled together for forming a complete 15 coop.

Still a further object is to provide a poultry coop, especially adapted to be positioned upon the running board of an automobile, and to have two decks therein, each 20 deck or compartment being accessible to, through a sliding door, the door of one compartment sliding over the door of the other compartment when moved to open position.

With these and other objects, in view, my invention consists in the construction, arrangement and combination of the various parts of my device, whereby the objects contemplated are attained, as hereinafter more 30 fully set forth, pointed out in my claims, and illustrated in the accompanying drawings, in which:

Figure 1 is a perspective view of my improved poultry coop.

Figure 2 is a sectional view taken on line 2—2 of Figure 1, showing how the bottoms are supported within the wire frame coop.

Figure 3 is a detail, sectional view taken on line 3—3 of Figure 1.

Figure 4 is a detail, sectional view taken on line 4—4 of Figure 1; and

Figure 5 is a detail, sectional view taken on line 5—5 of Figure 1 showing a sectional view through one of the end walls of the 45 coop.

In the accompanying drawings, I have referred to the front wall, back wall and top, as the unit A.

The front wall 10, the back wall 11 and 50 the top 12, which form the unit A, are made in a flat position, and are folded after the various strands of wire are connected together to form the three walls.

The unit A consists of a number of comparatively heavy strands of cross wires 13,

which are formed with hooks 14 at their outer ends.

Near the two ends of the various cross wires 13 are similar wires 15 which extend at right angles to the cross wires 13, and 60 serve to form the frame for maintaining the entire unit A in proper position.

A pair of wires 16 are connected to the cross wires 13 at right angles thereto near the center of the wires 13, which serve as a 65 bracing feature as well as means for supporting the doors for the coop, as will hereinafter be more fully set forth.

A number of comparatively light wires 17 are spot welded to the cross wires 13 at 70 spaced intervals, as clearly shown in Figure 1 of the drawings.

The front wall 10 between the two wires 16 is not formed with any of the wire 17, and this open space serves as a door opening 75 into the coop itself, as will hereinafter be more fully set forth.

Slidably mounted upon the two wires 16 in the front wall 10 are the upper and lower doors 18 and 19, respectively.

The doors 18 and 19 are formed by providing two spaced horizontal cross wires 20, which have their ends looped around the wires 16 for permitting them to slide thereon.

The wires 20 are connected together by vertical strands of wire 21. The doors 18 and 19 overlap each other somewhat, as clearly shown in Figure 1 of the drawings, and are capable of being moved to position 90 where they will completely overlap one another for permitting access into either the upper or lower deck of the coop.

The coop is formed with a pair of end walls B, which are formed of a strand of 95 wire 22 formed with three sides arranged at right angles to each other.

The lower ends of the vertical sides of the wire 22 are bent inwardly, as at 23, and then upwardly, as at 24.

A lower cross wire 25 is spot welded to the inturned portions 23 for completing the fourth side of the end walls B.

Vertical strands of wire 26 are connected to the horizontal portion of the wire 22 and 105 to the wire 25.

A second wire 27 extends parallel to the wire 25, and is fixed to the inner ends of the inturned portions 23, as clearly shown in Figures 3 and 4 of the drawings.

A cross wire 28 is connected to the upturned ends 24 of the wire 22, and spaced directly above the wire 27.

5 A bottom 29, preferably formed of wood, is received between the lower ends of the front and back walls of the unit A, and are received between the wires 27 and 28 of the end walls B wherein the bottom 29 is retained in proper position within the assembled coop.

10 Each of the cross wires 13 have their hooked ends 14 extended around the wire 22 of the end walls B. The hooked ends 14 are not closed until after the bottom 29 is 15 in place.

A bottom 30, which divides the coop into two compartments is also positioned within the coop before the hooked ends 14 of the wires 13 are closed.

20 In order to position the bottom 13 within the coop, I provide a pair of spaced wires 31 and 32 on the end walls B.

The wire 31 is positioned above the bottom 30 and is fixed to the vertical wires 26, 25 and to the vertical sides of the wire 22.

The wire 31 is formed with a pair of in-turned U-shaped portions 33 which limit any upward movement of the bottom 30.

30 The lower wire 32 is fixed to the vertical portions of the wire 22 and is formed with an inturned portion which serves as a support for the bottom 30.

35 The inturned portion of the wire 32, is clearly shown in Figure 2 of the drawings, partly in solid lines and partly in dotted lines.

40 From the construction of the parts just described, it will be seen that the wires 31 and 32 form receiving pockets for supporting the bottom 30.

45 The bottoms 29 and 30, when positioned within the coop, and after the hooked ends 14 are engaged around the wires 22, the coop will be rigid and capable of withstanding the ordinary usage to which coops of this kind are subjected.

50 The lower door 21 will of course remain in closed position on its own account, however, it is necessary to retain the upper door 18 in closed position, and in order to do so, I provide a hook 34 which extends around one of the cross wires 13 and is adapted to engage the cross wire 20 of the door 18.

55 One of the advantages of my coop resides in the fact that a great number of them can be shipped in nested position, that is, the front, back and top wall, which is manufactured in a unit can be positioned within another unit whereby a minimum amount of space is required for shipping and storing a number of coops.

60 The coops can be quickly and easily assembled by inserting the two bottoms 29 and 30 in their respective positions relative to

the end walls B, and thereafter extending around the same unit A.

When the hooked ends 14 of the unit A are 70 in closed position, then the coop is completely assembled ready for use.

The coop can be manufactured and marketed at a low cost due to the fact that the major portion thereof is manufactured of long strands of wire in a flat position and thereafter bent to form the various walls 75 required.

It may be here mentioned that by using long continuous strands of wire for forming the front, back and side wall, I get a greater amount of strength than if one piece were 80 used and spot welded to the various cross wires, which make up the frames for the various walls.

Some changes may be made in the construction and arrangement of the various parts of my invention, without departing from the real spirit and purpose of my invention and it is my intention to cover by my claims, any modified forms of structure or use of mechanical equivalents, which may 90 be reasonably included within their scope.

I claim as my invention:

1. A poultry coop comprising a front, back and top wall made as a single unit, end walls, means on said front and back 95 walls for connecting the end walls therebetween, a pair of spaced bottoms adapted to be supported on said end walls for forming the coop into two compartments, a door opening in the front wall of said coop, a 100 pair of slideable doors for the door opening, one for each compartment, the doors being slideable one over the other as and for the purposes stated.

2. A poultry coop comprising a front, 105 back and top wall made as a single unit, end walls, means on said front and back walls for connecting the end walls therebetween, a pair of spaced bottoms adapted to be supported on said end walls for forming the coop into two compartments, spaced wires on the front wall, the space between said wires forming a door opening leading into each of the two compartments, a door for each compartment, slidably mounted 110 upon said spaced wires, the bottom of one door and the top of the other door overlapping each other for permitting them to slide to position where one will completely overlap the other.

3. A poultry coop comprising a front, back and top wall made as a single unit, end walls, means on said front and back walls for connecting the end walls therebetween, a pair of spaced bottoms adapted to be supported on said end walls for forming the coop into two compartments, spaced wires on the front wall, the space between said wires forming a door opening leading into each of the two compartments, a door for 125 each of the two compartments, a door for 130

- each compartment slidably mounted upon said spaced wires, the bottom of one door and the top of the other door overlapping each other for permitting them to slide to 5 position where one will completely overlap the other and a latch for normally holding one of said doors in its closed position.
4. A poultry coop comprising a front, back and top wall made as a single unit, said 10 unit including a number of spaced cross wires, loops formed on the ends of said cross wires, wire strands secured to said cross wires at right angles thereto, a pair of end walls adapted to fit in between the front and 15 back walls of said unit, the loops of said cross wires engaging around portions of said end walls for rigidly maintaining the form and shape of the assembled coop, a bottom in said coop supported by said end walls 20 near the bottom ends thereof, said front wall having a door opening and a pair of slidable doors for said door opening.
5. A poultry coop comprising a front, back and top wall made as a single unit, said unit including a number of spaced cross wires, loops formed on the ends of said cross wires, wire strands secured to said cross wires at right angles thereto, a pair of end walls adapted to fit in between the front and back walls of said unit, the loops of said cross wires engaging around portions of said end walls for rigidly maintaining the form and shape of the assembled coop, a bottom in said coop supported by said end walls near the bottom ends thereof, a second bottom supported by said end walls above the first bottom for dividing the coop into two compartments and a pair of doors slidable one over the other for gaining access into the compartments of said coop, latch means 30 for one of said doors.

Des Moines, Iowa, November 28, 1924.

SETH S. BARKER.
